UNITED STATES PATENT OFFICE.

ETHEL G. STAFFORD, OF BRADENTON, FLORIDA.

DENTAL FLOSS HOLDER.

Application filed December 9, 1926, Serial No. 153,672. Renewed June 18, 1928.

This invention relates to dental floss holders of that type which includes a supply of floss within a container adapted to be drawn out and stretched between a pair of supports, 5 as used for dental purposes.

The main object of my invention is to provide a novel means for a device of this character wherein the floss after being drawn from the container and affixed in position on one 10 of the supports can be tightly stretched and held in that position for use.

Another object is to provide a spool or bobbin within the container for holding the floss and furnish novel means whereby the bobbin 15 may be positively rotated to tightly stretch the floss for use and then fix the bobbin with respect to such container but at the same time will permit the floss to be readily drawn from the bobbin on occasion.

20 Still another object is to provide a construction wherein the bobbin may have end-wise shifting movement whereby any particular zone from which the floss is being drawn will lie opposite the place from which 25 the floss is drawn for use.

Besides these objects the invention is directed to certain details of construction whereby the above objects may be attained.

In the appended drawing which shows two 30 preferred forms of the invention,

Figure 1 is a side elevation of one of the forms with parts broken away to show the interior arrangement.

Figure 2 is a plan of certain parts shown 35 in Figure 1.

Figure 3 shows the underside of the same parts.

Figure 4 is a longitudinal section of a portion of one of the parts shown in the previous 40 figures.

Figure 5 is an elevation of parts indicated in Figure 1 together with another part shown in section, all much enlarged.

Figure 6 is an end elevation of one of such 45 parts.

Figure 7 is an end elevation of another of such parts.

Figure 8 is an end elevation of a spool or bobbin.

50 Figure 9 is an end elevation of part of a support or arm.

Figure 10 is a plan of a slightly modified form of the device.

Figure 11 is a side elevation of the same, and

55 Figure 12 is a longitudinal section of parts shown in Figure 10, much enlarged.

In respect to the first nine figures of the drawing 1 is a member having two spaced supports or arms 2, 3 extending laterally 60 therefrom, the arm 3 in this instance having an aperture 4 therein through which to draw the floss indicated at 1' while the arm 2 as shown in Figure 9 may have a V-shaped notch 5 in its extremity in which to place the 65 floss. Just beneath the notch is a button 6 about which the floss may be wound after drawing it through the said notch, said button having a reduced neck 7 as shown in Figure 1 and as indicated in broken lines in said 70 Figure 9, about which to wind said floss.

The member 1 terminates in an extension 8 which may have a tapered bore 9, Figure 4, to receive one end of a tubular handle-portion 10, said end being tapered to fit snugly 75 into said tapered bore 9, Figure 1, the two portions 8 and 10 being thus securely held relatively. However, in addition, I may make use of an angular slot 11 in the extension 8, Figure 3, and fix a pin 12 in the handle-portion 10 to engage in said slot, it being understood that I may use either method described, or both. The outer end of the tubular handle is exteriorly threaded, not shown, to receive a threaded cap 13 to screw tightly 85 thereon. A shaft is designated at 14, one end of which is normally seated in a socket 15 of the member 1 disposed centrally of the bore 9 thereof, there being a key-way 16 in and extending along said shaft. A spool or 90 bobbin 17 having a central bore 18, Figure 8, is slidable along the shaft and has a suitable extension 19 to engage in said key-way. The opposite end of the shaft is reduced in diameter to provide a shoulder 20, the reduced end 95 passing through the mentioned cap 13, free to turn therein, and affixed at its extremity in any suitable or desired manner in the head 21. The latter on its inner face or that lying adjacent the cap 13 has one or more projections or ribs 22, preferably one at each side 100 of the shaft, adapted to enter any one of a

series of grooves 23 in the face of the said cap.

The spool or bobbin 17 is provided with windings of the floss, the extremity of the latter extending through the wall of the handle 10, in this instance, by providing a slot 10' in the latter, Figure 2, and there may be a notch 10² in the extension 8 to register with the said slot. When the handle and member 10 are assembled the slot at its bottom, and the said notch provide an opening through which the floss may be drawn without being pinched when the mentioned parts are firmly engaged.

15 The manner of operation is as follows: The wound bobbin is inserted into the socket 9 and the end of the floss drawn therefrom is threaded through the aperture 4 and secured upon the arm 2 by dropping it into 20 the notch 5 and securely winding it upon the button 6 so that it cannot slip, whereupon the handle 10 is seated in the socket 9 taking care that the slot 10' of the latter receives into it the floss where it extends from the 25 bobbin to the arm 3. Following this the shaft having the cap and head all permanently assembled, is inserted into the handle and into the bore 18 of the bobbin, the extension 19 of the latter being made to enter the key- 30 way 16, of course, and the shaft having been seated in the socket 15 is held in place by screwing the cap 13 in place.

Since the shaft is now in control of the bobbin that member may be rotated to draw 35 the floss tightly across the arms 2, 3 provided the ribs or fins 22 of the head 21 are disengaged from the grooves 23 of the cap 13. The floss having been stretched to the desired degree said fins may be now engaged 40 with said grooves, or one of them rather, and the floss is thus held tightly stretched. The depth of the socket 15 is of course sufficient to permit the shaft to have enough end play without leaving the same.

45 The permanent assembly of the shaft, cap and head is due to the fact that the shoulder at one side and the head at the other side of the cap prevents the latter being lost, there being sufficient play of the shaft 50 through the cap to provide the required movement of the head with respect to said cap.

It is to be noted that since the bobbin is free to shift along the shaft in either direction the floss as it unwinds will gradually cause such shifting. That part or zone of the bobbin from which the floss is being drawn may thus always lie beneath the opening created by the slot 10' and notch 10². That is 55 to say, said bobbin will travel practically its full length back and forth along the shaft as may be understood by referring to Figures 1 and 2.

In the last three figures of the drawing the 60 same ideas are included, making use, how-

ever, of a slightly different form of device and wherein 24 is the member corresponding to 1 of the earlier figures while the handle 25 which is not necessarily hollow has a cavityed enlargement 26, the bore of such cavity 70 lying transversely of said handle in this instance.

A threaded cap 27 screws upon the enlargement for closing the cavity and a shaft 28 shouldered at 29 as before carries a bobbin 30 slideable therealong and constructed as in Figure 8 to engage the key-way 31. A head 32 on the shaft has a pin 33 to engage the groove 34 of the cap as in the first instance. The floss extends from the bobbin to the 80 arms of the member 24 through an aperture 35 in the wall of the enlargement 26, and as in the first form described the bobbin is free to shift along the shaft to always properly present the floss to the aperture 35. A 85 clip 25' may be secured on the handle 25 for convenience in attaching the device to the pocket of a garment.

The device in either of its form may be 90 made of any desired material though that of a non-metallic nature is, of course, preferable so far, at least, as the parts 1 and 24 are concerned, using celluloid or kindred substance.

From what has been described and shown 95 it is clear that the floss may be positively controlled at all times. When first the floss is bridged across the arms and secured in either form of device it can be drawn tightly and secured through the instrumentality of the 100 described fins and grooves. And at any time while in use the tightening operation may be resorted to for taking up slack due to stretching of the floss. When desired to expose an unused portion of the floss across the arms 105 2, 3 the head 21 is shifted to disengage its fins whereupon the bobbin is free to turn and after fastening the end of the floss the tightening and securing can again be resorted to.

I wish to state that it is not my wish to be 110 confined to the exact structures shown and described but have shown preferred forms merely, though the structure illustrated will form the subject of some of the claims to follow.

I claim:

1. A dental floss holder including a handle and a pair of arms between which to stretch the floss, a bobbin for holding windings of the floss, a shaft carrying the bobbin and having positive control of the same, and means separate from the handle for fixing the shaft with respect to the handle, said bobbin being free to shift upon the shaft in a direction paralleling its axis of rotation as the floss is drawn therefrom.

2. A dental floss holder including a handle portion and a pair of arms between to stretch the floss, a bobbin concealed in the handle for holding windings of the floss, a support for 120 125 130

the bobbin controlling the same, there being an outlet for the floss in said handle, at a point between the ends of the bobbin an external part in position to be grasped for rotating the support, and means to fix the part with respect to said handle, said bobbin being free to shift on the support in a direction paralleling its axis of rotation and with respect to the said outlet of the handle.

10 3. A dental floss holder including a handle, a pair of arms fixed with respect to the handle across which to stretch the floss, a bobbin in the handle to hold windings of the floss, an operating part in position to be grasped and 15 in direct engagement with the bobbin for rotating the same, said bobbin and said part being normally free to rotate, and means to fix the operating part and the bobbin with respect to the handle, said bobbin being free to 20 shift parallel to its axis of rotation with respect to said operating part.

4. A dental floss holder including a handle, a bobbin for holding windings of the floss, an arm fixed with respect to the handle to which 25 the floss is attachable, operating means in positive control of the bobbin for stretching the floss between it and the arm, and means to fix the operating means with respect to the handle, said bobbin being free to shift in one 30 direction with respect to the operating means.

5. A dental floss holder including a handle, a bobbin within the handle for holding windings of the floss, an arm fixed with respect to the handle to which the floss is attachable, 35 operating means on which the bobbin is carried and by which it is rotated, said bobbin being free to change its position along and with respect to said operating means, and means separate from the handle to secure the operating 40 means with respect to the handle.

6. A dental floss holder including a handle, a bobbin in said handle for holding windings of the floss, an arm extending from the handle to which the floss is attachable, there being 45 an opening in the handle through which the floss extends from said bobbin to said arm, operating means in positive engagement with the bobbin for rotating the same, and means to fix said operating means with respect to the handle, said bobbin being free to change 50 its position in one direction with respect to said opening in the handle irrespective of the operating means.

7. A dental floss holder including a handle, 55 a bobbin for holding windings of the floss, an arm extending from the handle to which the floss is attachable, a shaft separate from the handle on which the bobbin is mounted and along which it is adapted to freely shift but otherwise fixed to said shaft to turn therewith, said shaft adapted to be manually rotated, and means to fix the shaft with respect to the handle.

8. A dental floss holder including a 60 hollow handle, a shaft extending longitudinally

through said handle and including at one end a grasping portion, there being a socket in the handle in which the other end of the shaft is rotatable, means to secure the shaft with respect to the handle, and a bobbin keyed on 70 the shaft and freely shiftable along the same.

9. A dental floss holder including a hollow handle having an outlet for floss, a shaft extending longitudinally through the handle, there being a socket within the handle to receive one end of the shaft, said shaft at its other end terminating outside the handle, means to fix the shaft with respect to the handle, and a bobbin on the shaft free to slide therealong opposite the said outlet for the 80 floss, said bobbin being held from rotation with respect to said shaft.

10. In a dental floss holder, a member including a bore, a tubular handle insertable at one end therein and having an opening in its 85 wall, there being a socket in said member at the bottom of the bore, a cap adapted for closing the opposite end of the handle, a shaft extending through the cap and seated in said socket and shiftable endwise in both, a head 90 on the shaft outside the cap, means to fix the head with respect to the cap, and a bobbin to hold windings of the floss, the same being keyed on the shaft, said bobbin being free to 95 shift along said shaft with respect to the said opening of the handle.

11. A dental floss holder including a member having a bore, one of the walls created by the bore having an angular recess opening through the end of the member, the latter having a bore of smaller diameter in the bottom of the first named bore, a tubular part adapted to enter the said first named bore and having a lateral extension to engage in the recess by a rotary movement of the part, there being a 100 notch in the end of the member and in the end of the part adapted to register when the member and part are assembled leaving an opening, a shaft extending through the tubular part adapted to seat in the described smaller 105 bore, a floss holding bobbin carried by and rotatable with the shaft and adapted to have endwise shifting movement thereon opposite the opening, a cap engageable with the outer end of the tubular part, the said shaft extending therethrough, and a head on the shaft outside the cap, the latter and said head having 110 complementary portions adapted to be engaged whereby to fix the two named elements 115 relatively.

12. A dental floss holder including a member having a bore, one of the walls created by the bore having an angular recess opening through the end of the member, the latter having a bore of smaller diameter in the bottom of the first named bore, a tubular part adapted to enter the said first named bore and having a lateral extension to engage in the recess by a rotary movement of the part, there being a 120 notch in the end of the member and in the end 125 of the part adapted to register when the member and part are assembled leaving an opening, a shaft extending through the tubular part adapted to seat in the described smaller bore, a floss holding bobbin carried by and rotatable with the shaft and adapted to have endwise shifting movement thereon opposite the opening, a cap engageable with the outer end of the tubular part, the said shaft extending therethrough, and a head on the shaft outside the cap, the latter and said head having complementary portions adapted to be engaged whereby to fix the two named elements 130

of the part adapted to register when the member and part are assembled leaving an opening, a shaft extending through the tubular part adapted to seat in the described smaller bore, a floss holding bobbin carried by and rotatable with the shaft and adapted to have endwise shifting movement thereon opposite the opening, a cap engageable with the outer end of

the tubular part, the said shaft extending therethrough, and a head on the shaft outside 10 the cap, the latter and said head having complementary portions adapted to be engaged whereby to fix the two named elements relatively in selective positions.

In testimony whereof I affix my signature.
ETHEL G. STAFFORD.
